BENCH LEG.

Application filed April 26, 1926. Serial No. 104,668.

This invention relates to a bench leg in which a pair of upright tubular posts are held in fixed spaced relation by a flat top plate and suitable cross bars connecting the posts in vertically spaced relation and suitably secured to the posts.

The main object is to construct a bench leg of this character from stock tubing and from stock sheet metal plates, all of which may be easily and quickly cut to the desired lengths and secured together to form a rigid, strong and durable bench leg capable of being manufactured and installed ready for use at a comparatively low cost.

Another object is to provide the top plate with a downwardly projecting flange along and against the outer face of one of the posts and formed with a rearwardly projecting ledge for receiving and supporting a backboard commonly used in work benches for supporting tools.

Other objects and uses relating to specific parts of the device will be brought out in the following description.

In the drawings:-

Figure 1 is a perspective view of a bench leg embodying the various features of my invention.

Figure 2 is a longitudinal vertical sectional view taken on line 2-2, Figure 1.

Figure 3 is a fragmentary sectional view taken on line 3-3, Figure 1.

Figure 4 is a horizontal sectional view, partly broken away, taken in the plane of line 4-4, Figure 2.

As illustrated, this bench leg comprises a pair of upright tubular metal posts -1- and -1'- preferably of uniform size and held in parallel spaced relation by a top plate -2- and cross bars -3- and -4-, the lower ends of the posts being seated in suitable foot plates -5- as shown more clearly in Figure 2.

That is, the foot plates -5- preferably consist of flat and substantially square or rectangular plates having central openings of substantially the same diameter as the posts -1- and -1'- in which the lower ends of the posts are tightly fitted and secured by welding, brazing or equivalent fastening means to hold them in fixed relation to their respective posts.

The top plate -2- is also preferably made of flat sheet metal of somewhat greater width than the diameter of the posts -1-

and -1'- and is also of greater length than the distance between the outer sides of the front and rear posts so that when placed upon the upper ends of the posts it will project laterally and forwardly and rearwardly beyond the same.

This top plate -2- is seated flatwise upon the upper end faces of the posts -1- and -1'- and is welded by brazing or otherwise thereto for rigidly and permanently connecting those parts and at the same time forming a flat surface for the reception of a table top as -a- shown by dotted lines in Figure 2 in addition to its function for bracing and holding the posts in fixed relation.

The rear end of the plate -2- is provided with an integral depending flange -6- extending downwardly along the rear face of the rear post -1'- and also brazed, welded or otherwise secured thereto, the lower edge of said flange being offset rearwardly to form a ledge -6'- which serves to receive and support a backboard as -a'-, the rear edge of said ledge being in approximately the same vertical plane as the corresponding edge of the adjacent foot plate -5-.

The top plate -2- and flange -6- are provided with screw or bolt openings -7- for the reception of suitable screws or bolts by which the table top -a- or back piece -a'- may be secured in place. The upper cross bar -3- is preferably made of flat bar steel of approximately the same length as the distance between the posts -1- and -1'- and is adapted to be placed edgewise vertically with its upper edge resting against the lower surface of the top plate -2- to which it is welded or otherwise secured while the ends of the bar -3- abut against the inner faces of the posts -1- and -1'- and are similarly secured thereto by welding, brazing or equivalent fastening means.

The cross bar -4- is preferably tubular and has its opposite ends in apertures -4'- in the inner sides of the posts -1- and -1'- intermediate the ends thereof so as to project part-way into the interiors of said posts as shown in Figure 2, said cross bar -4- being brazed or otherwise secured in the openings -4'- to form a rigid permanent connection therewith for additionally placing the posts and holding them in parallel relation.

A bench leg constructed in the manner de-

scribed permits the use of stock tubing —1— and —1'— and for the cross bar —4— while the top members —2— and —3— may be made of flat sheet metal purchased in stock 5 and cut and bent to the required size and form thus permitting the bench leg to be made and installed at a comparatively low cost.

What we claim is:—

- 10 1. A bench leg comprising a pair of upright tubular posts, a flat top plate welded flatwise against the upper end faces of the posts and provided at its rear end with a downwardly projecting flange engaged 15 with the outer side face of the adjacent post,

said flange having its lower end provided with a rearwardly projecting ledge for supporting a back board.

2. A bench leg as in claim 1 including a 20 flat metal cross bar arranged edgewise vertically and having its upper edge welded to the lower face of the top plate and its ends welded to the inner faces of the upper portions of the posts.

In witness whereof we have hereunto set 25 our hands this 14th day of April, 1926.

HENRY B. HURSH.
CARL J. ANDERSON.
WILLIAM M. BARTELS.
